UNITED STATES PATENT OFFICE.

ALBERT H. WINTER JOYNER, OF TORONTO, ONTARIO, CANADA.

POLE-TOP LAMP-FIXTURE.

1,125,111.

Specification of Letters Patent. Patented Jan. 19, 1915.

Application filed July 7, 1914. Serial No. 849,381.

To all whom it may concern:

Be it known that I, ALBERT H. WINTER JOYNER, a subject of the King of Great Britain, and resident of the city of Toronto, county of York, Province of Ontario, in the Dominion of Canada, have invented certain new and useful Improvements in Pole-Top Lamp-Fixtures, described in the following specification and illustrated in the accompanying drawings, that form part of the same.

The principal objects of the invention are, to facilitate the placing and removal of the lamps and globes and to obviate the breaking or damaging of the globe cap and lamp in the event of the breaking of the globe.

A further object is to devise a form of fixture in which the cap is rigidly supported in such a manner that the cleaning of the globe would not be interfered with.

The principal feature of the invention consists in the novel construction and arrangement of parts, whereby the lamp and the electrical connections thereto are rendered readily separable from the base and electrical feed connections, and whereby the lamp and globe cap are rigidly supported from the base.

In the drawings, Figure 1 is an elevational and part vertical sectional view of a lamp fixture constructed in accordance with this invention. Fig. 2 is a perspective detail of the interior support for the globe cap showing the electrical block connector, and Fig. 3 is a sectional detail through one of the globe ring supporting lugs. Fig. 4 is an enlarged vertical sectional detail of the lower end of the lamp supporting member and of the separable electrical connections.

Like numerals of reference indicate corresponding parts in each figure.

Referring to the drawings, 1 is the base ring adapted to rest upon the pole top flange 2 having an outwardly projecting weathering flange at the bottom and downwardly extending lugs 3 to engage the inner side of the flange 2, the ring being held in place by the bolts 4. The upper side of the ring 1 is formed with a channel groove 6 adapted to receive the bottom rim 5 of the globe 7.

8 is a V-shaped bracket secured to the inner side of the ring 1 and extending centrally thereacross and supporting a suitable form of electrical screw socket 9 centrally arranged.

10 is a spider ring having the outwardly

projecting arms 11 adapted to rest upon the inner flange 12 of the base ring 1.

13 are lugs projecting inwardly from the ring 10 and supporting an electrical plug 60 connector 14 which is adapted to screw into the socket 9. The plug is provided with a central stem 15 adapted to engage one electrical terminal in the socket and the outer shell 16 forms the contact with the other 65 terminal.

17 is a socket formed in the spider 10 preferably arranged at an outward incline in which the lower end of the supporting tube 18 is secured, said tube being held rigidly in place by the pin 19. The tube 18 is preferably flattened above the ring and is bent into perpendicular position having the upper extremity round and upon this upper extremity is secured a spider 20.

21 is the globe cap here shown of spun metal, formed in two sections, though it must be understood that any desirable form may be used, said cap being secured to the arms of the spider 20, the globe cap is thus 80 rigidly supported from the base.

22 is a lamp socket suitably secured in the top of the globe cap and carrying the inverted lamp 23.

From this description it will be seen that 85 the globe cap is rigidly supported from the ring 1 and the plug 14 is rigidly secured to said ring. The electric wires 24 connect to the lamp socket at the top leading downwardly through the tubular support 18 and 90 immersing from the bottom are connected to the terminals of the plug consequently when it is desired to remove the lamp or to obtain access to the interior of the globe it is merely necessary to rotate the globe cap 95 and through the tube support 18 the plug 14 will be unscrewed from the socket 9, thereby disconnecting the lamp and also removing the cap and inner frame work and allowing the globe to be lifted off and 100 readily cleaned. The electrical plug and socket connections for the removable lamp supporting member are herein shown and described as being of the "screw" variety but any desirable form of separable electrical connectors may be used. It will also be seen that in the event of the globe being broken the supporting tube 18 will carry the globe top and lamp without injury. The support 18 is flattened intermediate of its 105 length in order to reduce the shadow on the globe to the smallest possible extent.

The ring 1 is provided with suitable ducts 25 extending angularly downward and outward from the groove 5 so that rain falling upon the globe will be drained to the exterior of the fixture.

26 is a reflector of cone shape supported upon the ring 10 below the lamp and adapted to direct the rays of light outwardly to the globe.

10 What I claim as my invention is:—

1. A pole top lamp fixture, comprising, a globe supporting base, an electrical connection arranged upon said base, a removable member extending upwardly from said base 15 and having an electrical connection at its lower end engaging the electrical connection in said base, and a lamp supported upon said removable member and electrically connected with the electrical connection carried thereby.

2. A pole top lamp fixture, comprising, a globe supporting base, an electrical connection arranged upon said base, a removable member extending upwardly from said base 25 within the globe, and having an electrical connection at its lower end engaging the electrical connection in said base, a lamp socket supported from the upper end of said removable member and electrically connected 30 with the electrical connection at the lower end of said member.

3. In a pole top lamp fixture, a rigid globe supporting base, an electrical socket rigidly supported from said base, a removable member supported upon said base, an electric plug connection secured to said removable member and adapted to engage said socket, an arm rigidly secured at one side of said removable member and extending 40 upwardly within the globe, a globe top rigidly connected to the upper end of said arm, and an inverted lamp socket secured in said globe top and electrically connected with the plug connection carried by said removable member.

4. In a pole top lamp fixture, a globe supporting ring carried on the pole top, a member removably supported on said globe ring having an annularly arranged socket therein, a tubular arm rigidly secured in said socket and extending outwardly and upwardly therefrom, a bracket member secured to the upper end of said arm, a globe cap rigidly secured to said bracket member, 50 a lamp socket secured in said globe cap, an electrical plug connection carried on said removable member and electrically connected to the lamp socket through said tube, and an electrical socket connection rigidly 55 connected from said globe ring.

60 5. In a pole top lamp fixture, a globe sup-

porting ring carried on the pole top, a member removably supported on said globe ring having an annularly arranged socket therein, a tubular arm rigidly secured in said 65 socket and extending outwardly and upwardly therefrom, a lamp socket carried at the upper end of said arm, an electrical plug connection carried on said removable member and electrically connected to the lamp 70 socket through said tube, and an electrical socket connection rigidly supported from said globe ring.

6. In a pole top lamp fixture, a globe ring secured to the pole top, a removable member supported on said globe ring and carrying a centrally arranged electrical connection, a co-mating electrical connection rigidly supported from the globe ring, a tubular member rigidly secured in said removable member and extending outwardly and upwardly therefrom and flattened intermediate of its length to substantially oval shape, a globe cap secured to the upper end of said tubular member, a lamp socket carried in said globe cap, and electric wires leading from said lamp socket through said tube to the lower electrical connection carried in said rotatable member.

7. In a pole top lamp fixture, a globe ring 90 adapted to rest upon the pole top and to be rigidly secured thereto having an annular channel in its upper side adapted to receive the bottom ring of the globe, said channel having downwardly and outwardly extending drain holes, a ring member removably supported upon the inner flange of the channel shaped globe ring, a tubular arm rigidly secured in said removable member and extending upwardly, a lamp socket arranged 100 at the top of said tubular arm, an electrical plug carried on said removable member and electrically connected with said socket through said tubular arm, and an electric socket rigidly supported from the globe 105 ring.

8. In a pole top lamp fixture, a globe ring adapted to be rigidly secured to the pole top, a removable member supported upon said globe ring, a globe cap rigidly supported 110 from the member carried on said globe ring, a lamp socket carried in the globe cap, and a centrally arranged cone shaped reflector carried on the lower portion of said removable member below the lamp.

Signed at the city of Toronto, county of York, Province of Ontario, in the Dominion of Canada, this 2nd day of July 1914.

ALBERT H. WINTER JOYNER.
